UNITED STATES PATENT OFFICE.

FREDERIC E. FARWELL, OF FITCHBURG, MASSACHUSETTS.

BENCH FOR CIRCULAR SAWS.

SPECIFICATION forming part of Letters Patent No. 380,560, dated April 3, 1888.

Application filed September 19, 1887. Serial No. 250,045. (No model.)

To all whom it may concern:

Be it known that I, FREDERIC E. FARWELL, of Fitchburg, in the county of Worcester, State of Massachusetts, have invented certain new and useful Improvements in Benches for Circular Saws, of which the following is a description sufficiently full, clear, and exact to enable any person skilled in the art or science to which said invention appertains to make and use the same, reference being had to the accompanying drawings, forming part of this specification, in which—

Figure 1 is a vertical longitudinal section of a saw-bench provided with my improvement, represented as in use, certain parts being shown in side elevation; Fig. 2, a vertical transverse section of the same, taken on line xx in Fig. 1; and Fig. 3, an elevation showing certain details of construction.

Like letters of reference indicate corresponding parts in the different figures of the drawings.

My invention relates more especially to means for adjusting the table of a bench; and it consists in a novel construction and arrangement of parts, as hereinafter more fully set forth and claimed, the object being to produce a simpler and more effective device of this character than is now in ordinary use.

The nature and operation of the improvement will be readily understood by all conversant with such matters from the following explanation.

In the drawings, A represents the body or frame of the bench, B the table, and C the circular saw.

The body is of the form and construction usual in benches of this description, the saw C being journaled on a shaft, m, in said body and driven by any suitable means. The table B is hinged at x to the rear end of the body A, and is provided with a slot, z, through which the saw C protrudes.

Journalized on bolts v to each of the side timbers, d, of the body A, in front of the saw C, there is an upwardly-projecting arm or plate, g, the upper edge of which is rounded, as shown at i in Fig. 1. These plates are connected at their lower ends by a cross-bar, h, on the upper side of which are disposed standards t, in which is journaled a roll, k.

Secured to the inner face of the front cross-timber, l, of the body there is a downwardly-projecting bracket, p, (see Fig. 4,) in the lower end of which is pivoted a horizontally-arranged tubular box, r. A rod, w, is mounted in this box, said rod being provided at its outer end with a hand-wheel, D, by means of which it may be revolved. The rod w is screw-threaded at its inner end and enters a screw-threaded hole, b, (see Fig. 2,) formed centrally in the roll k, said roll serving as a nut for said screw.

To the under side of the table B are secured longitudinally-arranged grooved tracks or ways H, so arranged that the tops i of the plates g will slide therein.

In the use of my improvement it will be obvious that by turning the wheel D to the right or left the roll k will be caused to travel on the rod w and the plates g to swing on the bolts v, the upper ends of said plates being moved back and forth in the tracks H, thereby causing the table B to be raised or lowered, as the case may be.

Having thus explained my invention, what I claim is—

1. In a saw-bench, the table B, provided with the grooved tracks H and hinged to the body A, in combination with the plates g, pivoted to said body and having their upper ends disposed in said tracks, and a screw for actuating said plates and raising and lowering the table, said screw working in a support on the frame-work of the machine and in a pivoted roll or nut connected with said plates, substantially as set forth.

2. In a saw-bench, the plates g, connected by the bar h and pivoted to the body A, the standards t, mounted on the bar h, the roll k, journaled in said standards and provided with the screw-threaded hole b, the tubular box r, pivoted in the bracket p, the screw-threaded rod w, mounted in the tube r and provided with the wheel D, and the table B, hinged to the body A and provided with the grooved ways H, all being constructed, combined, and arranged to operate substantially as set forth.

FREDERIC E. FARWELL.
